UNITED STATES PATENT OFFICE.

ADELBERT E. BRONSON, JR., OF CLEVELAND, OHIO.

DESIGN FOR A SHELL FOR COFFEE-MILLS.

No. 37,965.

Specification for Design.

Patented April 24, 1906.

Application filed March 9, 1906. Serial No. 305,184. Term of patent 14 years.

To all whom it may concern:

Be it known that I, ADELBERT E. BRONSON, Jr., a citizen of the United States, residing at Cleveland, in the county of Cuyahoga and State of Ohio, have invented a new, original, and ornamental Design for Shells for Coffee-Mills, of which the following is a specification, reference being had to the accompanying drawings, forming a part thereof.

Figure 1 is a perspective view of a shell of

a coffee-mill, showing my new design. Fig. 2 is a side elevation of the same.

I claim—

The ornamental design for a shell for a coffee-mill, as shown.
